UNITED STATES PATENT OFFICE.

LUCIAN NARVEL SIMMONS, OF HUNTINGTON, WEST VIRGINIA.

SHOE-CLEANER.

1,168,341.

Specification of Letters Patent. Patented Jan. 18, 1916.

Application filed September 27, 1915. Serial No. 52,905.

To all whom it may concern:

Be it known that I, LUCIAN N. SIMMONS, a citizen of the United States, residing at Huntington, in the county of Cabell and State of West Virginia, have invented a new and useful Shoe-Cleaner, of which the following is a specification.

The present invention appertains to shoe cleaners, and this application is a sequel of my application for patent on improvements in shoe cleaners filed February 9, 1915, Serial No. 7,032.

It is the object of the invention to provide a novel and improved device for cleaning shoes, boots and other articles of foot wear, the structure embodying brushes mounted in a novel manner for cleaning the dirt and dust from the shoe or other article of foot wear.

Another object of the invention is the provision of unique means for holding the parts assembled, and whereby they can be readily separated for purpose of cleaning, repair or replacement.

It is also within the scope of the invention to provide a shoe cleaner having the characteristics above noted, and which is comparatively simple and inexpensive in construction, as well as being convenient and practical in use.

With the foregoing and other objects in view which will appear as the description proceeds, the invention resides in the combination and arrangement of parts and in the details of construction hereinafter described and claimed.

The invention is illustrated in the accompanying drawing, wherein:

Figure 1 is a plan view of the device. Fig. 2 is a longitudinal section thereof taken on the line 2-2 of Fig. 1. Fig. 3 is a cross section taken on the line 3-3 of Fig. 2.

In carrying out the invention, there is employed a base or board 1, which can be nailed or otherwise fastened upon a step, porch or other support, although it is to be understood that the base or board 1 may be part of the step, porch or other support, since the bottom plate 2 of the cleaner can be applied either to an independent base or to the step or other support directly.

The bottom plate 2 which is constructed of sheet metal, and which is rectangular, is disposed upon the base 1 in an inclined position so as to slope toward one end of the base, and the bottom plate 2 is provided at

its ends with downturned flanges 3 and 4. The flange 3 at the lower end of the plate 2 overlaps the outer or free end of the base 1, and the flange 4 at the upper end of the plate 2 seats upon the base 1 and holds the plate 2 in an inclined position, so that water will be shed off of the plate 2 and base 1. The flange 3 is provided with any suitable number of apertures 5, and a similar number of pins or lugs 6 are carried by the respective end of the base 1 and are engageable through the apertures 5 when the plate 2 is moved onto the base longitudinally. The lugs 6 in the extending through the apertures 5 will assist in holding the plate 2 in position upon the base. The plate 2 is provided between its ends with an opening or aperture 7, and an upstanding screw eye 8 which is secured to the base 1 is projectable through the aperture 7 when the plate 2 is swung downwardly upon the base. This further assists in holding the plate 2 against displacement when the parts are assembled, it being noted that when the screw eye 8 projects through the aperture 7, the flange 3 is held against the respective end of the base 1 with the lugs 6 projecting through the apertures 5.

The bottom plate 2 is provided at its side edges with upturned flanges 9, and those halves of the flanges 9 adjacent that end of the plate 2 having the flange 3 have upwardly projecting wings or extensions 10. A bottom brush 11 is seated upon the flanges 9, and one end of the back of the brush has loosely connected thereto, a hook 12 which is engageable with the eye of the screw or keeper 8, to hold the brush 11 upon the flanges 9 and against the wings 10. Furthermore, the hooks 12 in engaging the screw eye or keeper 8 will prevent the plate 2 from being lifted, and this will hold the several foregoing parts assembled, until the hook 12 is released, which will at once allow the several parts to be separated easily. The back of the brush 11 is provided with longitudinal rabbets 13 at its side edges receiving the upper edges of the flanges 9, so that the brush 11 is held in place, and the bristles of the brush project upwardly to engage the sole and heel of the articles of foot wear. When the hook 12 is released, the brush 11 can be removed and the bottom plate 2 can then be swung upwardly and moved longitudinally to be disengaged from the base 1.

A pair of transverse scraper blades 14—15 are terminally riveted or otherwise secured to the wings 10, said wings projecting above the brush beyond one end thereof, and the 5 scraper blade 14 being disposed adjacent the respective end of the brush 11, while the other scraper blade 15 is disposed remote from the brush and higher up than the blade 14. The scraper blades 14—15 enable 10 the mud or dirt to be scraped from the heel and toe of the shoe in a convenient manner, especially in conjunction with the bottom brush 11. The device is also equipped with a pair of side brushes 16 at the opposite 15 sides of the bottom brush 11, the bristles of the brushes 16 projecting inwardly toward one another, and the backs of the brushes 16 being secured upon pairs of standards 17 which are provided at their lower ends 20 with inturned angularly extending portions 18 slidable through apertures in the flanges 9 below the brush 11. The bottom plate 2 is provided between the flanges 9 under the brush 11 with upstruck ears 19 through 25 which the portions 18 of the standards are slidable, and the ears 19 preferably engage the bottom of the brush 11 to assist in supporting the same, as will be apparent by reference to Fig. 3. Nuts or adjustable elements 20 are threaded upon the ends of the portions 18, and coiled wire expansion springs 21 are disposed upon said portions 18 between the ears 19 and nuts 20, whereby 30 the standards 17 and brushes 16 carried thereby inwardly toward one another. The tensions of the springs 21 can be regulated by adjusting the nuts 20. The side brushes 16 are thus yieldably mounted, whereby they can 35 separate to accommodate various widths of shoes. When the shoe is moved between the brushes 16, said brushes can yield or separate to properly accommodate and clean the sides of the shoe, while the brush 11 will 40 clean the bottom of the shoe.

The present device can be used for conveniently and effectively cleaning shoes or other articles of foot wear, it being preferable, in using the cleaner, to place the shoe 45 over the scrapers 14—15, and to then draw the shoe over the scrapers and between the brushes 16. The mud and dirt is thus scraped off of the heel and toe, and the sides and bottom of the shoe will then be cleaned 50 by the brushes. If desired, the shoe can be moved back and forth between the brushes 16 and over the brush 11 until the shoe is 55 cleaned or polished thoroughly.

Having thus described the invention, what 60 is claimed as new is:

1. A shoe cleaner comprising a bottom having upturned flanges, a removable brush seated upon said flanges, means for holding the brush upon said flanges, the flanges having 65 wings projecting upwardly above the

brush beyond one end thereof, and a pair of transverse scrapers carried by said wings, one adjacent said end of the brush and the other remote from the brush and higher up than the aforesaid scraper. 70

2. A shoe cleaner comprising a bottom having upturned flanges, a removable brush seated upon said flanges, said flanges having wings projecting upwardly above said brush at one end thereof, a transverse scraper carried by said wings, one end of the brush seating against said wings, and means for holding the brush upon said flanges and against said wings. 75

3. A shoe cleaner comprising a bottom 80 plate having upturned flanges and upstruck ears between said flanges, standards having inwardly projecting angularly extending portions at their lower ends slidable through said flanges and ears, side brushes carried by 85 the upper ends of said standards and having bristles projecting toward one another, nuts threaded upon the ends of said portions, and coiled wire expansion springs upon said portions between said ears and nuts. 90

4. A shoe cleaner embodying a base, a bottom plate seated thereon, the base having a keeper projecting through the bottom plate, a brush seatable upon the bottom plate, and movable means carried by the brush engageable with said keeper for holding all of said parts assembled. 95

5. A shoe cleaner embodying a base, a bottom plate seated thereon and having an opening, the base having an upstanding keeper projecting through said opening, the bottom plate having upturned flanges, a brush seated upon said flanges, and a hook carried by the brush and engageable with said keeper to hold the parts assembled. 105

6. A shoe cleaner embodying a base, an inclined bottom plate thereon having down-turned flanges at its ends, one overlapping one end of the base, the other seating upon the base to support the bottom plate in an inclined position, the first mentioned flange and said end of the base having interengageable means, the base having a keeper projecting through said plate, said plate having upturned flanges at its side edges, and a brush seating upon said flanges and having means engageable with said keeper to hold the parts assembled. 110

7. A shoe cleaner comprising a base, an inclined bottom plate thereon having down-turned flanges at its ends, one overlapping one end of the base, and the other seating upon the base to support the plate in inclined position, said plate having an opening between its ends, the base having an upstanding keeper projecting through said opening, said plate having upturned flanges at its side edges, those portions of the side flanges adjacent the first mentioned down-turned flange having upwardly projecting 120 125 130

wings, a transverse scraper carried by said wings, a brush seating upon said flanges and bearing at one end against said wings, and a hook connected to said end of the brush 5 and engageable with said keeper to hold the parts assembled.

In testimony that I claim the foregoing.

as my own, I have hereto affixed my signature in the presence of two witnesses.
